UNITED STATES PATENT OFFICE.

CYRIL G. PULLIN, OF ISLEWORTH, ENGLAND.

EXHAUST SILENCER FOR INTERNAL-COMBUSTION ENGINES.

Application filed April 12, 1920. Serial No. 373,038.

To all whom it may concern:

Be it known that I, CYRIL GEORGE PULLIN, a subject of the King of Great Britain, residing at Isleworth, Middlesex, 5 England, have invented certain new and useful Improvements in or Relating to Exhaust Silencers for Internal-Combustion Engines, of which the following is a specification.

10 This invention relates to exhaust silencers for internal combustion engines and has particular reference to that type of engine working on the two-stroke principle.

The silencing of a small two-stroke petrol engine is an entirely different proposition to that to be dealt with in a four-stroke cycle engine. On the four-stroke cycle engine the exhaust is expelled by the positive stroke of the piston, which practically expels the 20 exhaust gas from the cylinder, and further allows the use of a silencing means having a heavy internal resistance to the passage of the gas.

On a two-stroke cycle engine, the exhaust 25 is expelled from the cylinder by the relatively feeble blast of the incoming charge; to obtain therefore the required cooling and the maximum silencing effect for the engine it is necessary to allow the maximum 30 quantity of fresh fuel to enter the cylinder, that is, the exhaust and silencing arrangement must be as free as possible.

Now according to the present invention I provide a silencer in which the inlet for 35 the exhaust gases opens into the large end of a tapering chamber, the gases being then converged by the tapering contour of the chamber, whereon a high velocity for the gases is obtained, the gases then being directed into the large end of a second tapering chamber and so on through a required plurality of compartments tapered longitudinally and disposed so that the 40 large end of the first compartment adjoins the exhaust connection and the smaller end of the same compartment connects with the large end of the next compartment, the outlet pipe of the cylinder communicating 45 with the small end of the last of said compartments.

One construction of exhaust silencer embodying the present invention is illustrated by way of example in the accompanying drawings, in which Fig. 1 is a perspective 55 view of the silencer, Fig. 2 is a perspective view of the member (detached) which di-

vides the interior of the silencer into compartments, and Fig. 3 is a view of the end cap of the silencer.

In the construction here illustrated the 60 silencer 1 comprises two tapering compartments 2 and 3 formed by the single V-shaped one-piece baffle 4 disposed within the rectangular body of the silencer 1, and this baffle piece 4 is so disposed therein as to 65 leave a third narrow chamber or compartment 5 between one of its limbs and the wall of the body of the silencer.

The baffle plate 4 is fixed in position in the silencer body by any convenient means 70 such as for instance by welding it to the body.

Into the large end of the first compartment 2 there leads the inlet pipe 6 for the introduction of the exhaust gases, which on 75 entering the tapering chamber 2 proceed to the narrow end thereof, and then pass through perforations in the end of one limb of the V-shaped baffle and enter the large end of the second tapering compartment 3. 80 The gases again proceed to the narrow end of this chamber and pass out by way of the perforations 8 in the adjacent end of the second limb of the V-shaped baffle, into the chamber or compartment 5 between the 85 side of the silencer body and the baffle.

From the narrow chamber 5 the exhaust gases pass out of the silencer by an opening or slit 9 made in the cap 10 which fits over the end of the silencer body 1. This 90 cap is secured to the body by means of a bolt 11 passing through eyes 12 in opposite flanges of the cap 10 and through holes in the ends of opposite sides of the body 1 and bolt 11 is secured in position by a nut 95 16. The bolt 11 also passes through the ends of the V-shaped baffle 4.

Externally of the bolt 11 there is arranged a sleeve 17 which serves as a distance piece between the opposite sides of the body 1, 100 and this sleeve 17 is also held in position by means of a short "eye" bolt 13 which passes through a hole 18 in the head of the cap, the "eye" 14 of the bolt embracing the sleeve 17, and has a wing nut 15 screwed 105 over its outer end tight down on the cap 10.

The cap above described may be fitted to either end of the silencer, and it facilitates cleaning or inspection of the silencer, being easily removable. 110

I claim:

1. An exhaust silencer for internal com-

2

bustion engines comprising a casing divided internally into a plurality of tapering chambers by baffles in which the gases enter at the larger end of each chamber in succession and pass by way of openings in the baffles at the smaller end of the chamber into the larger end of the succeeding chamber, and a relatively narrow chamber to which the gases from the last tapering chamber pass before leaving the silencer.

10 2. An exhaust silencer for internal combustion engines comprising a casing, a baffle therein dividing the casing internally into two chambers each with a wide end and a narrow end, the wide end of one chamber adjoining the narrow end of the other, a port admitting exhaust gases to the wide end of one chamber and a port between the narrow end of that chamber and the wide end of the adjoining chamber.

15 3. An exhaust silencer for internal combustion engines comprising a casing, a V-shaped baffle therein so disposed that it divides the casing internally into three chambers, two of which each have a wide end and a narrow end, the wide end of one chamber adjoining the narrow end of the other, a port admitting exhaust gases to the wide end of one chamber, a port between the narrow end of that chamber and the wide end of the adjoining chamber, and a port from the narrow end of the second chamber into the third chamber.

20 4. An exhaust silencer for internal combustion engines comprising a casing, a V-shaped baffle therein disposed with one limb oblique to the adjoining side of the casing and the second limb substantially parallel to the opposite side of the casing, and dividing the casing internally into three chambers, two tapering and one substantially of even sectional area throughout.

25 5. An exhaust silencer for internal combustion engines comprising a casing, baffles therein dividing the casing into three chambers two of which are tapering and a detachable cap over one end of the casing having an opening in it through which the gases leave the third chamber.

6. An exhaust silencer for internal combustion engines comprising a casing, baffles dividing the casing internally into a number of chambers through which the exhaust gases pass in succession, a detachable cap at one end of the casing, means adapted to secure the cap to the casing and spacing means between the opposite walls of the casing adapted to hold same apart when the cap is secured in position.

7. An exhaust silencer for internal combustion engines comprising a casing, a V-shaped baffle therein, so disposed that the casing is divided into three compartments, two adjacent tapering compartments, and a third of substantially even sectional area throughout, port admitting exhaust gases to the wide end of one tapering compartment, openings in said baffle connecting the smaller end of the last mentioned tapering compartment to the large end of the other tapering compartment openings in the said baffle connecting the smaller end of the said other tapering compartment with the third compartment of even sectional area, a detachable cap on the outlet end of said casing, means adapted to secure the caps to the casing, spacing means adjacent the cap between the opposite walls of the casing, and an outlet opening in said cap registering with the outlet end of said compartment of even sectional area.

75 In testimony whereof I affix my signature.

CYRIL G. PULLIN.
